UNITED STATES PATENT OFFICE.

ROBERT F. FRIEDRICH, OF PHILADELPHIA, PENNSYLVANIA, ASSIGNOR TO WEBER & FRIEDRICH, INC., OF PHILADELPHIA, PENNSYLVANIA, A CORPORATION OF PENNSYLVANIA.

DESIGN FOR A STOCKING.

Application filed January 18, 1927. Serial No. 20,420. Term of patent 14 years,

To all whom it may concern:

Be it known that I, ROBERT F. FRIEDRICH, a citizen of the United States, and a resident of Philadelphia, in the county of Philadelphia, State of Pennsylvania, United States of America, have invented a new, original, and ornamental Design for a Stocking, of which the following is a specification, reference being had to the accompanying drawing, forming part thereof.

Figure 1 is a view in side elevation of a stocking showing my new design, the stocking being shown in the distended position which it assumes when worn.

I claim:

The ornamental design for a stocking substantially as shown.

ROBERT F. FRIEDRICH.
